CLAIM

The ornamental design for a brewer, as shown and described herein.

DESCRIPTION

FIG. 1 is a perspective view of a brewer showing a first embodiment of our design;

FIG. 2 is another perspective view of the first embodiment;

FIG. 3 is a front elevation view of the first embodiment;

FIG. 4 is a rear elevation view of the first embodiment;

FIG. 5 is a left-side elevation view of the first embodiment;

FIG. 6 is a right-side elevation view of the first embodiment;

FIG. 7 is a top plan view of the first embodiment;

FIG. 8 is a bottom plan view of the first embodiment;

FIG. 9 is a perspective view of a brewer showing a second embodiment of our design;

FIG. 10 is another perspective view of the second embodiment;

FIG. 11 is a front elevation view of the second embodiment;

FIG. 12 is a rear elevation view of the second embodiment;

FIG. 13 is a left-side elevation view of the second embodiment;

FIG. 14 is a right-side elevation view of the second embodiment;

FIG. 15 is a top plan view of the second embodiment; and,

FIG. 16 is a bottom plan view of the second embodiment.

The broken lines shown in the drawings represent environment and form no part of the claimed design.
